UNITED STATES PATENT OFFICE.

AUGUST DORN, OF NEWARK, NEW JERSEY, AND CHARLES M. CRANDALL, OF MONTROSE, PENNSYLVANIA; SAID DORN ASSIGNOR TO SAID CRANDALL, WM. R. BECKWITH, AND FREDERICK W. CRANDALL, OF MONTROSE, PA.

DOLL-HOUSE, &c.

SPECIFICATION forming part of Letters Patent No. 243,873, dated July 5, 1881.

Application filed May 17, 1881. (No model.)

To all whom it may concern:

Be it known that we, AUGUST DORN, of the city of Newark, county of Essex, and State of New Jersey, and CHARLES M. CRANDALL, of Montrose, in the county of Susquehanna and State of Pennsylvania, have invented a new and useful Improvement in Doll-Houses, &c.; and we do hereby declare that the following is a full, clear, and exact description of the same, reference being had to the accompanying drawings, making part of this specification.

This invention is in the nature of an improvement in adjustable doll-houses and furniture; and the invention consists in an adjustable doll-house and similar toys constructed with hinged sides, back, and roof, whereby these several parts, when folded, and the floor of the house, &c., form a box to contain the furniture and other articles placed within it, all constructed, arranged, and combined in the manner hereinafter more particularly described.

In the accompanying sheet of drawings, Figure 1 represents a perspective view of our doll-house in the unfolded position, as when in use; Fig. 2, a perspective view of same when folded together; and Fig. 3, a longitudinal section of the folded house, showing furniture packed within same.

Similar letters of reference indicate like parts in the several figures.

In the doll-houses heretofore made their bulk rendered them objectionable for the purpose of packing and shipping, and the cost of freight added materially to their expense. By our invention, however, the house, when prepared for packing and shipping, is reduced to the smallest possible compass, and it forms a box or case to contain the furniture with which the house is furnished.

To that end we construct the house with a floor, A, of any suitable size. At right angles

to the upper surface of this floor are permanently fixed the lower portions, a, b, and c, of the sides and back of the house. To these fixed portions of the sides and back are respectively secured, by hinges d, the upper sections of the sides and back B, C, and D. To the upper edge of the back, D, is hinged a sectional roof, E. This roof is formed substantially of two pieces of wood, e and f, joined at their edges at right angles, so that when the front section, e, rests upon the sections B and C of the sides it forms, to some extent, a peaked roof, as is shown in Fig. 1. The house may be provided with two or more windows, g and h, and a removable chimney, k, may be fitted to the roof, if desired.

Now, our house, when in the position just described, and as is shown in Fig. 1, with its furniture displayed upon its floor, is the semblance of a completed and furnished house, and can be played with as such; but when it is desired to pack the house and its furniture for shipment, or so that it will occupy the least possible space, the furniture is laid compactly on the floor A, the hinged sections B and C of the walls are turned down and inward, and the hinged section D of the back is likewise folded down until it rests on the fixed walls a b, forming the top, and the roof folds down, inclosing and forming the edge of what, in this way, becomes substantially a box, within which all of the furniture and the chimney k, which has been removed for that purpose, are placed. When the house is in this folded position it becomes a neat box, of inconsiderable size, which may be then shipped and packed, by the dozen, in a comparatively small space and without much risk of breakage.

When the walls and back are raised to form the house, spring-clamps i or similar devices may be employed to keep the several parts in position.

It is obvious that our invention applies equal-

ly well to toy stables, cupboards, dressers, and sideboards, and other toy articles of manufacture.

Having thus described our invention, what we claim as new, and desire to secure by Letters Patent, is—

1. In a toy house, &c., sections thereof hinged, whereby the house may be folded into box form, and contain the furniture therein, substantially as and for the purpose described.
2. In a toy house, &c., hinged sides B C, back D, and roof E, in combination with

spring-catches, whereby the several sections may be held in position, substantially as described.

AUGUST DORN.

CHARLES M. CRANDALL.
